SIGNAL SYSTEM

Willard P. Place, Wilkinsburg, Pa., assignor to
The Union Switch & Signal Company, Swiss-
vale, Pa., a corporation of Pennsylvania

Application February 17, 1939, Serial No. 256,946

12 Claims. (Cl. 246—63)

My invention relates to signal systems, and more specifically to signal systems for railways.

I shall describe one form of apparatus embodying my invention, and I shall then point out the novel features thereof in claims.

Code signal systems have found widespread use, and in railway signaling code signal systems are now of common practice. In many of the code signal systems for railways an alternating current of a selected frequency, preferably 100 cycles per second, is coded by being periodically interrupted, the interruptions being preferably of the code frequencies of 180, 120 and 75 cycles per minute. Each of such code frequencies is assigned to reflect a particular traffic condition. For example, as generally used, the 180 code frequency reflects a clear traffic condition, the 120 code frequency reflects an approach medium traffic condition, the 75 code frequency reflects an approach traffic condition, and no current reflects a stop or slow speed condition. In such codes of alternating current the "on" and "off" periods are of substantially equal duration. In the 180 code frequency, for example, each cycle is one-third second in duration, and current is supplied ("on" period) for substantially one-sixth second, and no current is supplied ("off" period) for substantially one-sixth second.

The alternating current is usually distributed from a central power station to the different signaling points along the railway by a transmission line formed by line wires strung on a pole line along the right of way and line transformers one at each signaling point. The primary control circuit is the track circuit of an insulated track section, and coding apparatus codes the alternating current supplied to the track circuit according to traffic conditions in advance of that track section. In such cab signal systems a receiving circuit is mounted on the train in inductive relation with the track rails to inductively receive an electromotive force in response to each period alternating current flows in the track circuit. A code following relay governed by the receiving circuit is operated to one position when the alternating current flows in the track circuit, and is operated to a second position when the alternating current ceases. Hence the code following relay has substantially equal "on" and "off" periods of operation. That is, the period the relay remains at the position effected by the presence of current ("on" period) and the period the relay remains at the position effected by the absence of current ("off" period) are substantially equal. The decoding apparatus governed

by the code following relay for selectively controlling a cab signal in accordance with the different codes of alternating current is constructed for most satisfactory operation when the code following relay is operated with substantially equal "on" and "off" periods. Again, when the track relay controlled by the track circuit of each track section is a code following relay and this track relay governs a wayside signal through the medium of a decoding relay means, it is desirable to effect substantially equal "on" and "off" periods of operation for the code following track relay. That is to say, the decoding relay means now in general use in railway code signal systems operates most effectively and satisfactorily when the "on" and "off" operation periods of the code following relay are equal.

Furthermore, the filter preferably associated with the receiving circuit of the present code signal systems for railways is sharply tuned to the frequency of the alternating current which, as stated hereinbefore, is preferably 100 cycles per second.

Other code signal systems have been proposed for railways which use coded impulses of direct current. The direct current is supplied from batteries or other sources of unidirectional current located one at each signaling point, the control circuit being the track circuit the same as in coded alternating current systems. The coding apparatus at each signaling point so interrupts the supply of unidirectional current to the track circuit of the associated track section that the current impulses of direct current have different code frequencies according to different traffic conditions in advance of that section. The current impulses of direct current would preferably be of the 180, 120 and 75 code frequencies the same as under the coded alternating current systems. These systems using such coded direct current do not require a constantly energized transmission line, and hence are free from delays to traffic should all line wires be destroyed by a storm. The direct current impulses are in each case of relatively high peak voltage and of short duration. The high peak voltage is an aid to the shunting sensitivity of the track circuit and also effects, when the section is occupied by a train, surges of current of high amperage which is an aid to the inductive transfer of energy to train carried receiving circuits. The current impulses are, as stated above, of short duration, the duration of each current impulse being only a small portion of the code cycle, and hence the energy output required of the battery is relatively low.

With code following relays operated to a first position during the presence of current and operated to a second position during the absence of current, it follows that in systems of the code impulse type (coded direct current) the "on" period of the code following relay is relatively short compared with the "off" period of the relay. Such limping operation of the code following relay may not, therefore, effectively operate the present decoding apparatus which, as stated hereinbefore, is constructed for substantially equal "on" and "off" periods of the code following relay.

A feature of my present invention is the provision in signal systems of the code impulse type of novel and improved means for transmitting code impulses of direct current of the present code frequencies which are effective to operate code following relays with substantially equal "on" and "off" periods and the present standard decoding means can be used. Another feature of my invention is the provision of novel and improved coding means wherewith the direct current code impulses transmitted thereby effectively influence the present receiving circuits which are, as stated hereinbefore, sharply tuned for reception of alternating current of 100 cycles per second. Thus a train equipped with standard train carried cab signal apparatus will be controlled when the train is moving over a track circuit using coded direct current supplied by apparatus embodying my invention equally as well as when the train is moving over a track circuit supplied with the present coded alternating current. Still another feature of my invention is the provision in code signal systems of the impulse type of novel means for checking the proper occurrence of the current impulses supplied to the track circuit. Other features and advantages of my invention will appear as the specification progresses.

For a better understanding of my invention, reference can be had to the accompanying drawings in which Figs. 1a and 1b are diagrammatic views of a preferred form of apparatus embodying my invention when applied to a railway signal system, Fig. 1a being the trackway portion of the apparatus and Fig. 1b being the train carried portion of the apparatus. Fig. 2 is a view partly diagrammatic and partly in plan of a coder or code transmitter that may be used in the trackway apparatus of Fig. 1a. Fig. 2a is a detail of the coder of Fig. 2. Fig. 3 is a diagram illustrating the operation of certain circuit controlling contacts of the coder of Fig. 2. Figs. 4a and 4b are diagrams illustrating operating characteristics of the direct current impulses produced by the coder of Fig. 2 under certain conditions and of the electromotive forces effected by such impulses. Figs. 5a and 5b are diagrams illustrating operating characteristics of direct current impulses produced by the coder of Fig. 2 under certain other conditions and of the electromotive forces effected by these latter impulses.

In each of the several views like reference characters designate similar parts.

It will be understood that I do not wish to limit my invention to signal systems for railways and this one application of apparatus embodying my invention will serve to illustrate the many places where the apparatus will be useful.

Referring to Fig. 1a, a railway over which traffic normally moves in the direction indicated by an arrow has its track rails 1a and 1b formed by the usual insulated rail joints into consecutive track sections of which only section W—X and 75 the adjoining ends of the two sections adjacent

thereto are shown for the sake of simplicity. Each track section is provided with a track circuit which comprises means for supplying coded unidirectional current across the rails at the exit of the section and a receiving and decoding relay 5 means connected across the rails at the entrance of the section. Looking at track section W—X, coded unidirectional current is supplied to the rails adjacent the exit of the section through the medium of a battery TB, a first and a second track 10 transformer T1 and T2, coding apparatus indicated as a whole by the reference character CT, and associated circuits, the code frequency supplied being governed by traffic controlled relays XA, XR and XL to be later described. 15

Before proceeding further with the description of the apparatus of Fig. 1a, it should be pointed out that in several instances the contact fingers of relays XA, XR and XL are shown remote from the windings of the relays in order to simplify the 20 drawings. In each such instance the contact finger is identified by the reference character of the relay and is shown in the position corresponding to the normal energized or deenergized condition of the relay winding. 25

The secondary windings of the transformers T1 and T2 are each connected across the track rails 1a and 1b over circuits which are so controlled that only one secondary winding is connected with the rails at a time. The secondary 30 winding 2 of track transformer T1 has its left-hand terminal connected with rail 1a over wire 3, and has its right-hand terminal connected with rail 1b over four alternate paths, the first one of which includes wire 4, front contact 5 of relay 35 XA and wire 6. The second path includes wire 4, back contact 7 of relay XA, front contact 8 of relay XR and wires 9 and 6. The third path includes wire 4, back contact 7 of relay XA, back contact 10 of relay XR, lower winding 11 of a 40 polar relay PR to be later described, front contact 12 of relay XL, wire 13, contact M1 of a coder or code transmitter C120 also to be later described, and wires 9 and 6. The fourth path is the same as the third path up to winding 11 of 45 relay PR, thence over back contact 14 of relay XL, wire 15, contact M1 of a code transmitter or coder C75 to be later described, and wires 9 and 6.

The secondary winding 16 of transformer T2 50 has its left-hand terminal connected with rail 1a over wires 17 and 3, while its right-hand terminal is connected with rail 1b over two alternate paths, a first one of which includes back contact 18 of relay XA, back contact 19 of relay XR, top winding 20 of polar relay PR, front contact 21 of relay XL, wire 22, contact M2 of coder C120 when closed as will later appear, and wires 9 and 6. The second path is the same as the first path up to winding 20 of relay PR, thence over back contact 23 of relay XL, wire 24, contact M2 of coder C15 when closed, and wires 9 and 6. It follows that when either relay XA or XR is picked up the secondary winding 2 of track transformer T1 alone is connected across the track rails, but when 65 both relays XA and XR are released and relay XL is picked up the secondary winding 2 of transformer T1 is connected across the rails serially with the lower winding 11 of relay PR and the contact M1 of coder C120, while the secondary winding 16 of transformer T2 is connected across the rails serially with the top winding 20 of relay PR and contact M2 of coder C120. When relays XA, XR and XL are all released, the secondary winding 2 of transformer T1 is connected across 70 75

the rails over a path serially including winding 11 of polar relay PR and contact M1 of coder C15, while the secondary winding 16 of transformer T2 is connected across the rails over a path serially including winding 20 of polar relay PR and contact M2 of coder C15. It should be here pointed out that when both relays XA and XR are released a short circuit path across the rails 1a and 1b can be traced from rail 1a over wires 17 and 83, back contact 84 of a relay 82 to be referred to later, back contacts 85 and 86 of relays XA and XR, respectively, and wires 87, 9 and 6 to rail 1b. The purpose of such short circuit path across the track rails will be more fully described hereinafter.

Condensers 27 and 28 are preferably connected across the primary windings 25 and 26, respectively, of transformers T1 and T2. The circuits by which current from battery TB is supplied to the primary windings 25 and 26 of transformers T1 and T2, respectively, will be taken up and pointed out in detail hereinafter.

The coding apparatus CT may take different forms and as here shown it comprises three separate code transmitters or coders C180, C120 and C15 of the well-known torsional type. For example, these coders may be of the form covered by the United States Letters Patent No. 1,858,876, granted May 17, 1932, to Paul N. Bossart for Coding apparatus, the coders C120 and C15 being modified by an improvement to be later described. Reference is made to the above Bossart Patent No. 1,858,876 for a full description of such coding apparatus, and the coders C180, C120 and C15 will be in the instant application described only to the extent necessary for a full understanding of my present invention and to describe the improvements herein provided for the coders C120 and C15.

Referring to Fig. 2, a magnetic core structure 29 is mounted on a frame 30 of suitable non-magnetic material such as brass. The core 29 terminates in two spaced pole pieces 29a and 29b and has mounted thereon a winding 31. An oscillatable armature 32 is secured to a shaft 33 in any convenient manner here shown as by set screw 32a in a hub of the armature. Shaft 33 is journaled in frame 30 so that the armature 32 is disposed for rotatable movement between the pole pieces 29a and 29b. The armature 32 is cylindrical in shape and is provided with an outer surface (see Fig. 2a) so shaped that when the armature is rotated in a first direction (counterclockwise in Fig. 2a) from a normal or biased position 55 the air gaps between the outer surface of the armature and the pole pieces 29a and 29b are gradually decreased, but if the armature is rotated in the opposite or second direction (clockwise in Fig. 2a) from such normal position the air gaps 60 are at first gradually increased and then abruptly increase. The armature 32 is biased to its normal position by a spiral spring 34 the outer end of which is secured to the frame 30 by screws 35 and its inner end is secured to the hub of armature 32 65 by screws 106. The coder is provided with a contact K1 for controlling the supply of current to winding 31 and which contact comprises a contact member 36 disposed for operation by rotation of shaft 33, and a stationary contact member 37, the arrangement being such that contact member 70 75

away from the normal position. The contact member 36 is connected with a terminal 38 through a suitable flexible connection 38a, while the contact member 37 is connected with one terminal of winding 31. When a source of direct current is connected at terminals B and C of Fig. 2 the winding 31 is energized and a magnetic flux is built up in the core 29 which attracts armature 32 against the force of the bias spring 34 in its first direction from its normal position, that is, armature 32 swings in the direction of the decreasing air gap. After a limited rotation of armature 32, the contact K1 is opened and the winding 31 is deenergized. Bias spring 34 now causes armature 32 to swing back toward its normal position and contact K1 is closed to again energize winding 31. Due to the inertia of the parts, armature 32 swings past the normal position in its second direction a limited distance before it is again rotated in its first direction due to the attraction created by the energization of winding 31. The parts are so constructed that armature 32 swings substantially equal distances each side of its normal position. It is clear that as long as the current source is connected at terminals B and C the armature 32 will oscillate at a frequency governed by the mass of the armature 32 and the stiffness of the spring 34. The parts of coder C180 of Fig. 1a are so proportioned and adjusted that its armature oscillates at the frequency of 180 cycles per minute or three cycles per second. Coders C120 and coder C15 are so proportioned and adjusted that their respective armatures oscillate at the code frequencies of 120 and 75 cycles per minute, respectively.

A contact M4 is carried on shaft 33 by means of clips 39. Contact M4 is preferably of the liquid flow type such as a mercury switch, a common construction of which consists of a glass envelope having two spaced metal electrodes and a quantity of mercury sealed therein, the arrangement being such that the mercury bridges the electrodes at certain positions of the envelope and the mercury flows away from the electrodes when the envelope is tilted. Contact M4 for each of the coders of Fig. 1a is so positioned on shaft 33 that the contact is closed at the normal position of the armature 32 and is tilted to open the contact as the armature swings in its first direction, and is reclosed as the armature swings back to its normal position and remains closed while the armature swings in its second direction. Hence, as illustrated in Fig. 3, where the black area represents the closed position of the contacts, contact M4 opens at the start of each operating cycle 40 of the coder (armature starts to swing in said one direction), is reclosed at the end of the first half period of the cycle (armature returned to normal position) and remains closed during the second half period of each operating cycle (armature 45 swings in said second direction and returns to normal position).

The construction thus far described for the coder is common for each of the coders C180, C120 and C15 and is substantially the construction of 65 the coding apparatus covered by the aforementioned Bossart Patent No. 1,858,876 except for the liquid flow type of contact. Coders C120 and C15 are each provided with an improvement which I shall now describe.

Again referring to Fig. 2, a second armature 40 is fixed on a hollow shaft 41 which is slipped over and rotates freely on shaft 33. Armature 40 is joined to the shaft 33 through a spiral spring 41, the outer end of spring 41 being secured to arma- 70 75

ture 49 through an L-shaped member 42 bolted to armature 40 at 43 and secured to the spring 41 at 44. The inner end of spring 41 is secured to a sleeve 45, which sleeve is in turn secured to the 5 shaft 33 by a set screw 46. Three contacts M1, M2 and M3 are mounted on the hollow shaft 47 through the medium of suitable clips 48. Contacts M1, M2 and M3 are preferably of the liquid flow type similar to contact M4. An electromagnet 49 normally energized by any convenient source of current such as a battery 50 dampens the motion of armature 40 by induction with the outer rim 40a of the armature 40, the outer rim of the armature passing between spaced pole 10 pieces of magnet 49, as will be readily understood by an inspection of Fig. 2.

The motion of armature 40 lags the motion of shaft 33 and armature 32 by an amount depending upon the mass of armature 40, the stiffness 20 of spring 41 and to a small extent by the damping of magnet 49. If spring 41 is a stiff spring, armature 40 will lag only a few degrees behind armature 32. If spring 41 is weak, the lag of armature 40 becomes greater. The actual 25 amount of lag can be readily controlled by adjusting the stiffness of spring 41. Magnet 49 produces damping which increases with increasing velocity of armature 40, the latter damping being desirable to prevent the amplitude of the 30 oscillation of armature 40 from becoming too great. It is obvious that the magnetic damping produced by magnet 49 can be replaced by vanes mounted on the outer rim of armature 40 to increase its air resistance.

35 As illustrated in Figs. 1a and 3, contacts M1, M2 and M3 are mounted in a position so that contacts M1 and M3 are closed and contact M2 is open at the start of each operating cycle, that is, at the normal position of the armature 33. As 40 armature 32 swings in its first direction away from the normal position, contact M1 is tilted to open. At a predetermined interval after contact M1 is opened, contact M2 is tilted to close, and then still later contact M3 is tilted to open. 45 As armature 32 swings back to its normal position to complete the first half or "cn" period of the cycle and then swings in its second direction, the contacts M3 and M1 are not reclosed and contact M2 is not again opened until predetermined 50 positions are reached in the second half period of the operating cycle of the armature 32 because of the lag of armature 40. I have found that with the construction described above contacts M1, M2 and M3 can be made to accurately and reliably open and close at selected 55 positions in the operating cycle of the coder. The utility of such improved construction for the coders C120 and C75 will appear as the specification progresses.

60 Referring again to Fig. 1a, the coder C120 is provided with an energizing circuit which includes terminal B of the current source, either back contact 79 of relay XR and front contact 51 of relay XA, or front contact 52 of relay XR, 65 winding of coder C120, contact K1 of coder C120 and terminal C of the current source. Coder C120 is provided with an energizing circuit including terminal B, front contact 54 of relay XL, back contact 55 of relay XR, back contact 70 56 of relay XA, winding of coder C120, its contact K1 and terminal C. The energizing circuit for coder C75 involves terminal B, back contact 58 of relay XL, winding of coder C75, its contact K1 and terminal C.

75 The M4 contact of each of the coders C120,

C120 and C75 controls a circuit by which current is supplied from battery TB to the primary winding 25 of transformer T1 and to the condenser 27. The circuit governed by contact M4 of coder C120 can be traced from the lower terminal of battery TB over contact M4 of coder C120, either front contact 60 of relay XA or front contact 61 of relay XR, wire 62, primary winding 25 of transformer T1 and condenser 27 in parallel, and wire 33 to the upper terminal of battery TB. The circuit governed by contact M4 of coder C120 involves the lower terminal of battery TB, contact M4 of coder C120, back contacts 64 and 65 of relays XA and XR, respectively, front contact 66 of relay XL, and then as previously traced. Again, a circuit can be traced from the lower terminal of battery TB over contact M4 of coder C75, back contact 67 of relay XL, and as previously traced.

Each of the M3 contacts of coders C75 and 20 C120 governs a circuit by which current is supplied from battery TB to the primary winding 26 of transformer T2 and condenser 28. Starting from the lower terminal of battery TB, one circuit includes contact M3 of coder C120, back contacts 68 and 69 of relays XA and XR, respectively, front contact 73 of relay XL, wire 71, condenser 72 and primary winding 26 in parallel, and wires 72 and 63 to the upper terminal of battery TB. The other circuit includes lower 30 terminal of battery TB, contact M3 of coder C75, back contact 73 of relay XL, and then as previously traced. As previously explained, the contacts M1 and M2 of coders C75 and C120 are interposed in the connection by which the transformer secondary windings 2 and 16 are connected across the track rails 1a and 1b.

It is to be seen, therefore, that when either relay XA is picked up closing front contacts 51 and 69, or relay XR is picked up closing front contacts 52 and 61, current is periodically supplied from battery TB to the primary winding 25 of transformer T1 and condenser 27 by virtue of the operation of the coder C120. That portion of each operating cycle of coder C120 that its contact M4 is closed, current flows and energy is stored in the magnetic circuit of transformer T1. When contact M4 is opened, the circuit is interrupted and the stored energy decays. The parts are so proportioned as to time constants for the circuit that the energy builds up in the magnetic circuit of transformer T1 rather slowly and the electromotive force thereby induced in the secondary winding 2 is of so small a magnitude that it can be neglected. When the circuit is interrupted, the energy stored in the magnetic circuit of transformer T1 decays rapidly and an electromotive force is induced in the secondary winding 2 of transformer T2 which in turn causes a current impulse to flow in the track circuit since the connection of secondary winding 2 to the track rails is now completed at front contact 5 of relay XA or at front contact 8 of relay XR. Transformer T1 and condenser 27 are so proportioned that when connected with the track rails the track circuit thus formed is an oscillatory circuit and the current impulse supplied to the track circuit in the manner just described has a damped wave form the frequency of which is governed by the 70 proportioning of the circuit. For reasons to later appear, the circuit parts are so chosen that the frequencies of the oscillations of the wave form are of the order of 100 cycles per second. As illustrated in Fig. 5a, the first half cycle of 75

the wave form of the track circuit current impulse is of relatively high peak voltage which, as is well known, aids the shunting sensitivity of the track circuit and which effects when the section is occupied by a train a current surge of high amperage which is an aid to the transfer of energy inductively to train carried apparatus. Furthermore, the duration of the current impulse is only a small portion of the cycle which 5

10 in the case of the 180 code frequency is substantially .3 second. In the event that both relays **XA** and **XR** are released and relay **XL** is picked up so that back contacts **56**, **64** and **68** of relay **XA**; back contacts **55**, **65** and **69** of relay **XR**; 15 and front contacts **54**, **66** and **70** of relay **XL** are closed, the coder **C120** is operated and the battery **TB** is intermittently connected with the primary windings **25** and **26** of transformers **T1** and **T2** through the medium of the contacts **M4** 20 and **M3** of coder **C120**. During the time contacts **M4** and **M3** of coder **C120** are closed, current flows to the primary windings **25** and **26** and energy is stored in the magnetic circuits of transformers **T1** and **T2**. When contact **M4** is opened, 25 the energy stored in transformer **T1** decays and a current impulse is supplied to the track rails because the secondary winding **2** is connected to the rails over back contacts **7** and **10** of relays **XA** and **XR**, winding **11** of relay **PR**, front contact **12** of relay **XL**, and contact **M1** of coder **C120** and since contact **M1** remains closed until 30 after contact **M4** of coder **C120** is opened. It is to be noted because relays **XR** and **XA** are released, closing back contacts **86** and **85**, the current impulse flows through the short circuit path rather than through the track rails of the section. The current impulse flowing through winding **11** of polar relay **PR** energizes that 35 relay, the energization being such as to cause polar contact members **76** and **77** to be operated to the right-hand positions. Shortly after this current impulse is supplied by transformer **T1**, the contact **M1** of coder **C120** is opened and contact **M2** is closed so that the secondary winding **40** **2** of transformer **T1** is disconnected from the track rails and the secondary winding **16** of transformer **T2** is connected thereto. A little later in the operating cycle of coder **C120** the contact **M3** is opened to interrupt the circuit to the primary winding **26** of transformer **T2** and condenser **28**, with the result that the energy stored in transformer **T2** quickly decays and induces an electromotive force in the secondary winding **16** of transformer **T2** which causes an 45 impulse of current to be applied across the track rails because relays **XA** and **XR** are released closing their back contacts **18** and **19**. Transformer **T2** and condenser **28** are preferably similar to transformer **T1** and condenser **27**, respectively, and hence the current impulse supplied through transformer **T2** is substantially of the same characteristics as that supplied through transformer **T1**. At the start this current impulse supplied 50 through transformer **T2** flows in the short circuit path rather than in the rails. This current impulse from transformer **T2** flows in the winding **20** of polar relay **PR** in a direction to cause the polar contact members **76** and **77** to be operated to the left-hand positions. It follows that 55 two current impulses are supplied during each operating cycle of coder **C120** and relay **PR** is operated in step with the current impulses. With relay **PR** operated current is reversibly supplied to the two half portions of the primary winding **78** of a transformer **T3**, the circuit for primary 60

winding **78** being completed over back contacts **79** and **80** of relays **XR** and **XA**, respectively. The electromotive forces induced in the secondary winding **81** of transformer **T3** are rectified by contact member **77** of relay **PR** and are supplied to the relay **82** as rectified current. After a few current impulses relay **82** is energized and picked up, opening back contact **84** to remove the short circuit path across the track rails. From this point on, the two current impulses supplied 65 during each operating cycle of the coder **C120** to the track circuit, flow in the rails of the section, the polar relay **PR** being also operated so that relay **82** is energized and remains picked up from one current impulse to the next by virtue of its slow release characteristics. Polar relay **PR**, transformer **T3** and relay **82** function therefore to check the presence of two impulses each operating cycle of coder **C120**. If impulses are supplied from transformer **T1** only, then 70 polar relay **PR** remains at its righthand position and relay **82** is released to complete the short circuit path across the track rails. Likewise, if impulses are supplied through transformer **T2** only, polar relay **PR** is held at its left-hand position and relay **82** is released to complete the short circuit path across the track rails. 75

If relay **XL** is released closing back contacts **58**, **61** and **73** at the same time that relays **XA** and **XR** are released, current from battery **TB** is supplied intermittently to the primary windings **25** and **26** of transformers **T1** and **T2** over the contacts **M4** and **M3** of coder **C15**. Since the contacts of coder **C15** are positioned similarly to the contacts of coder **C120**, two current impulses are supplied to the track rails during each operating cycle of coder **C15**, the windings **11** and **20** of polar relay **PR** being interposed in the connection with the track rails and relay **PR** operated by each current impulse. Again it should be noted that at the start of the operation of coder **C15** the track rails are short circuited over the path including back contact **84** of relay **82**, but that the relay **82** is shortly picked up to remove the short circuit if the current impulses are alternately supplied by the transformers **T1** and **T2**. 80

From the foregoing description it is to be seen that under traffic conditions that cause relay **XA** or relay **XR** to be picked up, coder **C180** is operated and a single current impulse is supplied to the track circuit of section **W-X** each operating cycle of the coder, the wave form of the current impulse being as illustrated by Fig. 5a. Under traffic conditions that cause relays **XA** and **XR** to be released and relay **XL** to be picked up, coder **C120** is operated and two current impulses are supplied to the track circuit each operating cycle of the coder, the two current impulses being spaced apart by a predetermined time interval by virtue of the setting of the contacts **M1**, **M2** and **M3** of coder **C120**. The relationship of the setting of the contacts of coder **C120** and the spacing of the two current impulses supplied each operating cycle is illustrated 85 by Figs. 3 and 4a. As illustrated in Fig. 4a, each current impulse has a damped wave form the same as explained in connection with the current impulse supplied to the track circuit when the coder **C180** is operated. 90

Under traffic conditions that cause relay **XL** as well as the relays **XA** and **XR** to be released, the coder **C15** is operated and two current impulses are supplied to the track circuit each operating cycle of coder **C15**, the impulses being spaced apart by a predetermined time interval by virtue 95

of the setting of the contacts of coder C75. The relationship of the setting of the contacts of coder C75 and the spacing of the current impulses supplied to the track circuit is illustrated by Figs. 3 and 4a the same as in connection with coder C120 except for the fact that the two current impulses supplied when coder C75 is operated are spaced somewhat farther apart than the two current impulses supplied when the coder C120 is operated. The use of such spacing of the two current impulses supplied each operating cycle of coder C120 or coder C75 will be described more fully hereinafter. Furthermore it is to be recalled that the fact that two current impulses are supplied each operating cycle of coder C120 or coder C75 is checked through the medium of polar relay PR and its associated apparatus.

The arrangement of a track transformer having a condenser connected across its winding and the two connected with the track rails so that the track circuit thus formed is an oscillatory circuit and the current impulse supplied to the track circuit when a direct current flowing in the transformer winding is interrupted has a damped wave form is disclosed and claimed in my copending application, Serial No. 239,523, filed November 8, 1938, for Signal systems.

Still referring to Fig. 1a, the receiving and decoding relay means for the track circuit of section W—X includes a filter WF, a code following relay WT, decoding unit DU1 and three control relays WA, WR and WL. As shown in Fig. 1a, the filter WF consists of an inductor 89 and two condensers 90 and 91. A portion of inductor 89 is connected across the rails 1a and 1b over condenser 90 and wires 92 and 93, and the full inductor 89 is connected with the winding of relay WT through a full wave rectifier 94. The filter WF is tuned to resonance at the frequency of 100 cycles per second. In other words, the circuit by which relay WT is connected across the track rails of section W—X is tuned to resonance at the frequency of the oscillations of the wave form of the current impulses supplied to the track rails through the medium of the apparatus located at the exit end of the track section. Since the current impulses supplied to the track circuit have a damped wave the oscillations of which are of the order of 100 cycles per second, the energy applied to filter WF sets up oscillation which persists in the filter circuit for several cycles longer than the current impulse. Fig. 5a illustrates the damped wave of the track circuit current impulses under the 180 code frequency, and Fig. 5b illustrates the oscillation set up in the filter WF by each such current impulse. I have found that at the 180 code frequency a single current impulse of relatively high peak voltage causes oscillation to persist in the filter circuit for an interval which is substantially equal to one-half of the cycle interval. In other words, the "on" period of the oscillations created by a single current impulse is substantially equal to the "off" period of the oscillations. The oscillations created in filter WF are rectified by rectifier 94 and are applied to the winding of the code following relay WT, with the result that the code following relay WT is operated at substantially equal "on" and "off" periods when the code impulses of the track circuit are of the 180 code frequency. At the 120 or 75 code frequency the "on" period of the oscillations created in the filter is not long enough to avoid a limping operation of the code following relay if only one current impulse is transmitted each cycle. For this

reason coders C120 and C75 are constructed to provide two current impulses each code cycle. Looking at Figs. 4a and 4b, when the oscillations set up by the first current impulse begin to decay, they are supported by fresh energy from the second current impulse. The two current impulses transmitted each code cycle are so spaced by virtue of the positioning of the contacts of the coder that the oscillations set up in the filter WF of the associated receiving means persist for substantially the first half period of the cycle interval and the code following relay of the receiving means is operated for substantially equal "on" and "off" periods. The difference between the two current impulses transmitted through the medium of coder C120 and the two transmitted through the medium of coder C75 lies in the fact that the two impulses under the 75 code frequency are spaced slightly farther apart than the spacing of the two current impulses under the 120 code frequency, this spacing being readily obtained by a proper setting of the contacts M1, M2 and M3 of the coder C75. The contact member 95 of code following relay WT is therefore operated at the code frequency of 180, 120 or 75 according to the code frequency of the current impulses supplied to the track circuit, the "on" and "off" periods of operation of relay WT being substantially equal for each of the different code frequencies.

Code following relay WT controls over its contact member 95 the supply of current to the decoding unit DU1, the current impulses supplied to the decoding unit DU1 being of a frequency corresponding to the code of the current impulses of the track circuit and being of substantially equal "on" and "off" periods because of the operation effected for the code following relay WT. The decoding unit DU1 may be of standard construction and it is deemed sufficient to say that relay WA connected with the output terminals of the unit DU1 is effectively energized and picked up only at the code frequency of 180, relay WR connected with the output terminals of the unit DU1 is effectively energized and picked up only when the code following relay is operated at the 120 code frequency, and relay WL connected with the output terminals of the unit DU1 is effectively energized and picked up at either the 75, 120 or 180 code frequency.

Control relays WA, WR and WL correspond to the control relays XA, XR and XL, respectively, and control the supply of track current to the coding apparatus for the track circuit for the section next in the rear of section W—X in the same manner that relays XA, XR and XL control the supply of current to the coding apparatus for the track circuit of section W—X. Furthermore, the control relays XA, XR and XL are controlled by the track circuit for the section in advance of section W—X through a filter XF, code following relay XT and decoding unit DU2 in the same manner that relays WA, WR and WL are controlled by the track circuit of section W—X.

As shown at the lower right-hand portion of Fig. 1a, the relays XA, XR and XL govern the operating circuits of a wayside signal XS, as will be readily understood by an inspection of Fig. 1a, and a detailed description of such operating circuits is not necessary since they are in accordance with standard practice and form no part of my present invention.

Referring now to Fig. 1b, the train carried apparatus includes two inductors 96 and 97 mounted on the train in inductive relation with track

rails 1a and 1b, respectively. Inductors 96 and 97 are connected through a condenser 98 with a portion of an inductor winding 99 of a filter TF, the connection of inductors 96 and 97 being such that electromotive forces induced therein by current formed in the rails in opposite directions add their effects. A condenser 100 is connected across the inductor winding 99 and the full winding 99 is connected with the input terminals of an amplifier AM over wires 102 and 103, the amplifier AM being preferably of the electron tube type. The output terminals of amplifier AM are connected over wires 104 and 105 with the winding of a master code following relay MR. Relay MR in turn controls over its contact member 101 the supply of current to input side of a decoding unit DU3 whose output terminals are connected with control relays TA, TR and TL. The decoding unit DU3 is preferably of standard construction and the arrangement is such that relay TA is effectively energized and picked up only in response to operation of the code following relay MR at the code frequency of 180 cycles per minute, relay TR is effectively energized and picked up only in response to operation of relay MR at the code frequency of 120, and relay TL is effectively energized and picked up when relay MR is operated at either the 180, 120 or 75 code frequency. The control relays TA, TR and TL are used to control train governing means here shown as a cab signal CS of the four indication position light type. The operating circuits for the cab signal CS will be readily understood by an inspection of Fig. 1b and the circuits need not be described in detail since they are of standard practice and form no part of my present invention.

The train carried apparatus of Fig. 1b is substantially that of standard practice in present day use in coded alternating current systems. It should be noted that filter TF interposed in the receiving circuit of amplifier AM is tuned to resonance at the frequency of 100 cycles per second. Furthermore, the decoding unit DU3 is, as stated hereinbefore, constructed for substantially equal "on" and "off" periods of operation of the associated code following relay MR.

I shall now point out the operation of the train carried apparatus of Fig. 1b by the trackway apparatus of Fig. 1a. I shall first assume that the train enters the track section W—X from the left and the traffic conditions in advance of section W—X are such as to cause relay XA to be picked up so that coder C180 is operated and current impulses of the code frequency of 180 are supplied to the track rails, a single current impulse being supplied each operating cycle of the coder C180 and the current impulse having a damped wave as illustrated in Fig. 5a. Each such current impulse induces an electromotive force in the train carried inductors 96 and 97 of relatively high peak voltage because of the high amperage of the current surge produced by the high peak voltage of the rail current impulse. The electromotive force induced in the inductors 96 and 97 set up in filter TF oscillations that persist for several cycles after the rail current impulse ceases because the filter TF is tuned to resonance at 100 cycles per second and the oscillation of the current impulse is of 100 cycles per second. As illustrated in Fig. 5b, the oscillations set up in filter TF persist for substantially one-half of the cycle interval. The energy of filter TF is applied to amplifier AM and after amplification the energy is effective to operate relay MR to its left-hand

position, relay MR being operated to its right-hand position when the oscillations in the filter TF cease. Hence the master relay MR is operated at the code frequency of 180 and the "on" and "off" periods of the operation of the relay are substantially equal the same as if the train on which the apparatus of Fig. 1b is mounted is moving over a track circuit supplied with alternating current coded at the 180 code frequency. With relay MR thus operated by the 180 code frequency, the relay TA is selected and the corresponding signal indication is effected for the cab signal CS.

I shall next assume that the traffic conditions in advance of section W—X are such as to cause relay XR to be picked up while relay XA is released. The coder C180 is operated and code impulses of current of the 180 code frequency are supplied to the track circuit of section W—X the same as previously described with the result that the cab signal CS displays the same signal indication. That is to say, the 180 code frequency for the track circuit of section W—X is effected in response to clear traffic conditions in advance and relay XA is picked up and is also effected in response to approach medium traffic conditions in advance and relay XR is picked up.

Assuming that the traffic conditions in advance of section W—X are such as to cause relays XR and XA to both be released while relay XL is picked up, the coder C120 is operated to cause two current impulses to be supplied to the track circuit each code cycle, the impulses being spaced apart a predetermined time interval by the positioning of the contacts of the coder C120 as illustrated by Figs. 3 and 4a. Each such current impulse induces electromotive forces in the inductors 96 and 97 that in turn set up oscillations in the filter TF, the oscillations effected by the second impulse beginning before the oscillations effected by the first impulse cease so that as is illustrated in Fig. 4b the oscillations applied to amplifier AM for operating relay MR persist for substantially one-half period of the code cycle. Hence the relay MR is operated for substantially equal "on" and "off" periods in response to the track circuit current impulses supplied by the apparatus of Fig. 1a under the 120 code frequency the same as it would be operated if the train was moving over a track circuit supplied with coded alternating current of the 120 code frequency. The current impulses supplied to the decoding unit DU3 will select relay TR which in turn will cause a corresponding signal indication for the cab signal CS.

In the event the traffic conditions in advance of section W—X are such that relays XA, XR and XL are all released, the coder C75 is made active and two current impulses are supplied to the track circuit each code cycle, the two current impulses being separated a predetermined time interval by virtue of the setting of the contacts of coder C75. Again, the oscillations set up in filter TF by the second current impulse of the track circuit begin before the oscillations set up by the first current impulse cease, with the result that the oscillations applied to amplifier AM for operating master relay MR persist for substantially one-half period of the cycle interval and the relay MR is operated at substantially equal "on" and "off" periods at the code frequency of 75. With relay MR thus operated at the code frequency of 75, relay TL only is energized and picked up and a corresponding signal indication effected for the cab signal CS. In the event the track

section W—X is occupied by a train in advance, then the track circuit is shunted by the leading train and no electromotive force is induced in the inductors 96 and 97, with the result the relay 5 MR is not operated and the control relays TA, TR and TL are all released to establish a corresponding signal indication for the signal CS.

It is clear from the foregoing description that the train carried apparatus of Fig. 1b, which is substantially that of standard practice for the present code signal system for railways, is effectively operated by the trackway apparatus of Fig. 1b equally as well as by track circuits using coded alternating current.

15 Although I have herein shown and described only one form of apparatus embodying my invention, it is understood that various changes and modifications may be made therein within the scope of the appended claims without departing 20 from the spirit and scope of my invention.

Having thus described my invention, what I claim is:

1. In a signal system for a railway whose track is formed into consecutive track sections each of 25 which is provided with a track circuit including a source of unidirectional current and each of which sections has associated therewith a control relay governed by traffic conditions in advance of the section the combination comprising, a coder for a section operative to divide time into successive operating cycles of a selected interval and provided with a first and a second contact which are operated a predetermined interval apart during the first half period of each of said 35 cycles, and circuit means including a contact of the control relay for said section and said first and second contacts of said coder to effectively couple the current source of the section with its track circuit to cause to flow in the track circuit during the first half period of each cycle two current impulses separated from each other by a predetermined interval.

2. In a signal system for a railway whose track is formed into consecutive track sections each of 45 which is provided with a track circuit including a source of unidirectional current and each of which sections has associated therewith a control relay governed by traffic conditions in advance of the section the combination comprising, a first and a second track transformer for a section each having a secondary winding connected across the track rails of the section, a coder operative to divide time into successive cycles of a selected interval and provided with a first and a second contact which are closed at the start of each 55 cycle and are opened a predetermined interval apart during the first half period of each cycle, a first circuit including a contact of the control relay for said section and said first contact of the coder to connect the current source of said section with the primary winding of said first transformer, and a second circuit including a contact of the control relay and said second contact of the coder to connect the current 65 source with the primary winding of said second transformer.

3. In a signal system for a railway whose track is formed into consecutive track sections each of which is provided with a track circuit including 70 a source of unidirectional current and each of which sections has associated therewith a control relay governed by traffic conditions in advance of the section the combination comprising, a coder for a section having a cyclic operation 75 of a predetermined frequency and provided with

a first and a second contact which are closed at the start of each said operation cycle and are successively opened at selected points of the first half period of the cycle, and circuit means controlled by the control relay of said section and including said first and said second contacts to supply from said source of current to the track circuit of said section a current impulse one when said first contact is opened and one when said second contact is opened to cause to flow in said track circuit during each said operation cycle two current impulses which are separated from each other.

4. In a signal system for a railway whose track is formed into consecutive track sections each of 15 which is provided with a track circuit including a source of unidirectional current and each of which sections has associated therewith a control relay governed by traffic conditions in advance of the section the combination comprising, a first and a second track transformer for a section each having a secondary winding connected across the track rails of said section, a polar relay having a first and a second winding, a coder for said section having a cyclic operation of a predetermined frequency and provided with two contacts which are closed at the start of each operation cycle and are successively opened at selected points of the first half period of the cycle, means controlled by the control relay of said section including said first winding of said polar relay and a first one of said coder contacts to connect the current source of said section with the primary winding of said first transformer to supply to the track rails during each said cycle a first current impulse, other means controlled by said control relay including said second winding of said polar relay and the other one of said coder contacts to connect said current source with the primary winding of said second transformer to supply to the track rails during each said cycle a second current impulse, said first and second windings of said polar relay poled to operate that relay to a first position in response to each of said first current impulses and to operate that relay to a second position in response to each of said second current impulses, and means controlled by said polar relay to check the successive occurrence of said first and second current impulses.

5. In a signal system for a railway whose track is formed into consecutive track sections each of which is provided with a track circuit including a source of unidirectional current and each of which sections has associated therewith a control relay governed by traffic conditions in advance of the section the combination comprising, a coder for a section having a cyclic operation of a predetermined frequency and provided with a pair of contacts which are closed at the start of each 35 said operation cycle and are successively opened at selected points of the first half period of the cycle, a first circuit means controlled by the control relay of said section including a reactance device and a first one of said coder contacts to supply 45 from the current source of said section to the track rails a first current impulse when said one contact is opened, a second circuit means controlled by said control relay including another reactance device and the other one of said coder contacts to supply from said current source to the track rails a second current impulse when said other coder contact is opened, a polar relay having a first winding interposed in said first circuit means and a second winding interposed in 55

5 said second circuit means, said first and second windings poled to operate said polar relay to a first position in response to said first current impulse and to operate that relay to a second position in response to said second current impulse, and means controlled by said polar relay to check the successive occurrence of said first and second current impulses.

6. In a signal system for a railway whose track 10 is formed into consecutive track sections each of which is provided with a track circuit including a source of unidirectional current and each of which sections has associated therewith a control relay governed by traffic conditions in advance 15 of the section the combination comprising, a coder for a section having a cyclic operation of a predetermined frequency and provided with a pair of contacts which are closed at the start of each said operation cycle and are successively opened 20 during the first half period of each cycle, a first and a second reactance device for said section having connection with the track rails and proportioned to form an oscillatory circuit therewith, a first circuit including a contact of 25 the control relay of said section and a first one of said coder contacts to connect the current source of said section with said first reactance device to cause to flow in the track rails when said one coder contact is opened a first current 30 impulse having a damped wave, a second circuit including a contact of said control relay and the other one of said coder contacts to connect said current source with said second reactance device to cause to flow in the track rails when said other 35 coder contact is opened a second current impulse having a damped wave.

7. In a signal system for a railway whose track is formed into consecutive track sections each of which is provided with a track circuit including 40 a source of unidirectional current and each of which sections has associated therewith a control relay governed by traffic conditions in advance of the section the combination comprising, a coder for a section having a cyclic operation of a predetermined frequency and provided with a pair of contacts which are closed at the start of each said operation cycle and are successively opened 45 during the first half period of each operation cycle, a first and a second reactance device having connections with the track rails of said section and each proportioned to form an oscillatory circuit therewith, circuit means controlled by the control relay of said section and including said pair of coder contacts to connect the current 50 source of said section with said reactance devices to cause when said coder contacts are opened during the first half period of each said cycle two spaced current impulses to flow in the track rails each of which impulses has a damped wave 55 of predetermined oscillation frequency, a code following relay, a receiving circuit to couple said code following relay with the track rails of said section and including a filter tuned to resonance at said oscillation frequency to supply to said 60 code following relay in response to said two spaced current impulses of each said operation cycle an energizing impulse that persists for substantially the first half period of the cycle, and a signal controlled by said code following relay.

8. In a signal system for a railway whose track is formed into consecutive track sections each of which is provided with a track circuit including a source of unidirectional current and each of which sections has associated therewith a control relay governed by traffic conditions in ad-

vance of the section the combination comprising, a coder for a section having a cyclic operation of a predetermined frequency and provided with a pair of contacts which are closed at the start of each said operation cycle and are successively opened 5 during the first half period of each operation cycle, energy storing means including capacity and reactance connected across the track rails of said section to form an oscillatory circuit therewith, circuit means including a contact of 10 the control relay of said section and said pair of coder contacts to connect the current source of said section with said energy storing means to cause to flow in the track rails of said section during the first half period of each said operation cycle two spaced current impulses each of which impulses has a damped wave of predetermined oscillation frequency, a code following relay, receiving circuit means to couple said code following relay with the track rails of said section and including capacitance and inductance to tune the circuit means to resonance at said oscillation frequency to cause an energizing impulse that persists for substantially the first half period of each 15 operation cycle of said code to be supplied to said code following relay in response to said two spaced current impulses of each operation cycle, and signaling means governed by said code following relay.

9. A railway signal system comprising, a receiving circuit mounted on a train in inductive relation with the track rails, a train-carried filter including capacitance and inductance and tuned sharply at a predetermined frequency, train-carried amplifying and decoding means connected to said receiving circuit through said filter for operating a cab signal in response to recurrent electromotive forces induced in the receiving circuit by current of a predetermined code flowing in the track rails when each cycle of such 40 code current consists of substantially equal on and off periods of current, a track section, a coder having an operation cycle equal to the cycle of said code current and provided with a first and second contact which are successively opened 45 in the order named during the first half period of each operation cycle, a source of direct current, and traffic controlled circuit means including capacitance and inductance to connect said source with the rails of said section over said 50 contacts to supply to the rails during the first half period of each said operation cycle two spaced current impulses which induce in said receiving circuit electromotive forces which are effective to cause oscillations of said predetermined frequency to persist in said filter during substantially the first half period of each cycle.

10. In a signal system for a railway whose track is formed with a track section to the rails of which a receiving circuit including a filter tuned 60 to resonance at a predetermined frequency is coupled and which receiving circuit has a decoding means connected therewith for operating a signaling device when alternating current of said predetermined frequency coded at a particular code rate is applied to said receiving circuit and such coded current has equal on and off periods, the combination comprising, a source of direct current, a coder having an operation cycle equal to the cycle period of said particular code rate and including a contact which is opened at the start of each operation cycle and reclosed at a selected point of the cycle, a transformer and a condenser, and circuit means including said transformer and condenser to con- 70

- nect said source of direct current to the rails of said section over said coder contact for supplying to said rails at the start of each said operation cycle a current impulse of a voltage and duration effective to shock excite said filter for causing current oscillations to persist therein for a period substantially equal to one-half of said code cycle period whereby said decoding means is effectively controlled to operate said signaling device.
11. In a signal system for a railway whose track is formed with a track section to the rails of which a receiving circuit including a filter tuned to resonance at a predetermined frequency is coupled and which receiving circuit has a decoding means connected therewith for operating a signaling device when alternating current of said predetermined frequency coded at a particular code rate is applied to said receiving circuit and such coded current has equal on and off periods, the combination comprising, a source of direct current, a coder having an operation cycle equal to the cycle period of said particular code rate and including a contact which is opened at the start of each operation cycle and reclosed at a selected point of the cycle, a transformer having a secondary winding connected with the rails of said section, and circuit means including said coder contact to connect said source of direct current to the primary winding of said transformer for storing up magnetic energy when the contact is closed and for supplying a current impulse to the rails when said contact is opened and which current impulse is characterized by a peak voltage effective to shock excite said filter for causing current oscillations to persist therein for a period substantially equal to one-half of said code cycle period and said decoding means is effectively controlled to operate said signaling device.
12. In a signal system for a railway whose track is formed with a track section to the rails of which a receiving circuit including a filter tuned to resonance at a predetermined frequency is coupled and which receiving circuit has a decoding means connected therewith for operating a signaling device when alternating current of said predetermined frequency coded at a particular code rate is applied to said receiving circuit, the combination comprising, a source of direct current, a coder having an operation cycle equal to the cycle period of said particular code rate and including a contact opened at the start of each operation cycle and reclosed at a selected point of the operation cycle, a transformer having a secondary winding connected with the track rails of said section, and circuit means including said coder contact to connect said direct current source with a primary winding of said transformer, said circuit means and transformer proportioned so that magnetic energy builds up slowly in said transformer when said contact is closed and decays rapidly when the contact is opened for supplying to the track rails unidirectional current impulses at said particular code rate with each impulse of a voltage and duration effective to shock excite said filter to cause current oscillations to persist therein for a preselected interval after the current impulse ceases whereby the decoding means is controlled to operate said signaling device.

WILLARD P. PLACE.
